A. H. HANDLAN

LANTERN

Filed April 21, 1922

Inventor:

A. H. Handlan

By Cook, McGehee, Atty.

Patented Dec. 18, 1923.

UNITED STATES PATENT OFFICE.

ALEXANDER H. HANDLAN, OF ST. LOUIS, MISSOURI.

LANTERN.

Application filed April 21, 1922. Serial No. 555,836.

To all whom it may concern:

Be it known that I, ALEXANDER H. HANDLAN, a citizen of the United States of America, a resident of the city of St. Louis and State of Missouri, have invented certain new and useful Improvements in Lanterns, of which the following is a full, clear, and exact description, reference being had to the accompanying drawings, forming a part of 10 this specification.

My invention relates to a lantern particularly adapted for the use of trainmen, and has for its object the production of an improved means for positively holding a lantern globe so as to prevent the egress of air currents between the globe and its seat.

Prior to this invention lanterns have been constructed with a seat for the base of the globe and an annular spring pressed globe holder engaging the upper portion of the globe. The spring pressed globe holder is adapted to slide within the dome, longitudinally thereof, and its function is to force the globe downwardly onto its seat, while at the same time centrally positioning the upper portion of the globe with respect to the dome. If the bottom face of the globe is properly and truly ground, no trouble is experienced with air currents entering the lantern between the globe and its bottom seat. In practice, however, it is found that many of the globes are not truly and properly ground on their bottom faces, this defect sometimes being so slight as to escape notice, and the defective lanterns are permitted to get into service when the difficulty of making the lantern operate properly is first detected.

In the giving of certain signals, it is imperative that the air entering the lantern shall be only from points of ingress definitely determined, in order that the flames may be sustained, thus permitting it to burn brightly. If during the giving of one of these signals a current of air be permitted to enter the lantern between the globe and its seat, the flame may be dimmed or quite probably completely extinguished. It is essential to avoid danger that the flame of the lantern be as nearly constant at all times as possible, and it is the object of the present invention to provide for an automatic adjustment, not only for properly ground globes, but for globes that are slightly defective in grinding, so that every lantern embodying my invention will have its globe

positively seated on its seat and the bottom face of said globe in contact at all points with the globe seat.

Lanterns have been produced heretofore which have been provided with spring pressed globe holders similar to that used in the present invention, but said globe holders were connected to the domes of the lanterns in such manner as to prevent the ready attaching or detaching of same. The particular object of this invention is to provide simple connecting means whereby the globe holders may be readily attached to and detached from the domes of the lanterns.

Fig. I is a side elevation of a lantern provided with my improved globe holder, parts of said lantern being broken away.

Fig. II is an inverted plan of the dome of the lantern shown in Fig. I, showing the globe holder in place therein, part of said dome and part of the guard wire by which it is supported being broken away.

Fig. III is a view of the globe holder and its associated spring, said globe holder being in section.

Fig. IV is an enlarged section on line IV-IV of Fig. I.

Fig. V is an enlarged plan view of a fragment of the globe holder showing the opening which receives the end of the attaching post.

In the drawing, A designates a lantern comprising an oil pot holder 1 secured to a guard frame 2, and provided with a depressed flat seat 3 adapted to receive the flat bottom face of the globe 4. A dome 5 is connected to the guard frame by means of a hinge 6.

The dome 5 is provided with the usual spring latch but as this forms no part of the present invention I do not deem it necessary to illustrate same.

Located in the dome 5 of the lantern is a globe holder in the form of a presser member 7, said presser member being forced onto the top face of the globe by means of a coil spring 8. The presser member preferably comprises an annular plate formed with a peripheral, upwardly extending flange 7' and is provided with a flat face engaging the flat top face of the globe 4. Said presser member is also provided with a diametrically arranged bar 9, the purpose of which will be subsequently pointed out. The coil spring 8, which forces the presser member tightly against the top face of the globe 4,

is interposed between the top of the dome 5 and said presser member, one extremity of said spring bearing against said dome top and the other extremity thereof bearing against that portion of said presser member within the upwardly extending flange 7. The dome 5 may be provided with the usual perforations 5' and the presser member 7 preferably has a circular row of air inlet openings or slots 7a near its outer edge.

The means for attaching the presser member 7 to the dome 5 of the lantern comprises a post 10, which is secured to the top of said dome in any suitable manner, such, for instance, as by riveting, and extends downwardly therefrom. The post 10 is circular in cross section and is provided at a point adjacent to its lower end with a winged portion comprising a pair of laterally extending lugs 11, which may be formed by displacing a portion of the metal of the post 10 to form said lugs, as shown in the drawing, or in any other suitable manner.

25 The diametrically arranged bar 9 of the presser member 7 is provided with an opening 12 corresponding to the cross sectional shape of the winged portion of the post 10.

In attaching the presser member 7 to the dome 5 through the agency of the post 10, said presser member is brought to a position where the portions of the opening 12 corresponding in shape to the lugs 11 are in registration with said lugs, whereupon said 30 presser member may be moved upwardly on the post 10, that portion of said post provided with the lugs 11 passing through said opening 12. After the presser member has been moved onto the post 10 in the manner 35 described, the presser member is rotated to a position where the lugs 11 do not register with the correspondingly shaped portion of the opening 12, thus causing said lugs 11 to contact with the solid portion of the bar 9 40 whereby said presser member is retained in place on said post 10.

45 It will be understood that the presser member, arranged to slide loosely on the post 10, will be automatically adjusted by the spring to firmly engage the top face of

the globe, and that the flat bottom face of the globe will engage the flat seat 3, thereby insuring a tight joint all around the bottom face of the globe whereby undesirable air currents are prevented from entering the 55 globe at its lower edge.

I claim:

1. A lantern having a dome, a globe, a seat for the bottom face of said globe, a spring-actuated presser member comprising an annular plate having a face which engages the top face of said globe, a post extending downwardly from the top wall of said dome on which said spring-actuated presser member is slidably mounted, said post being free from supporting devices below said top wall of said lantern dome and being provided with integrally formed projections adjacent to its lower end, said spring-actuated presser member being provided with an opening corresponding in shape to the cross sectional shape of said post at said projections, said spring-actuated presser member being adapted to be passed over said portion of said post bearing said projections and rotated a portion of a revolution to lock said spring actuated presser member on said post. 70

2. A lantern having a globe, a seat for the bottom face of said globe, a spring-actuated presser member comprising an annular plate having a face which engages the top face of said globe, an upwardly extending annular flange and a diametrically arranged bar, a post on which said spring-actuated presser member is slidably mounted, said post being provided with integrally formed projections adjacent to its lower end, said diametrically arranged bar of said spring connected presser member being provided with an opening corresponding in shape to the cross sectional shape of said post at said projections, said spring-actuated presser member being adapted to be passed over said portion of said post bearing said projections and rotated a portion of a revolution to lock said spring-actuated presser member on said post. 80 85 90 95

In testimony that I claim the foregoing I hereunto affix my signature.

ALEXANDER H. HANDLAN.
